UNITED STATES PATENT OFFICE.

JASMIN PIERRE BERGERON, OF LOS ANGELES, CALIFORNIA, ASSIGNOR OF ONE-HALF TO
HENRY C. SHIPPEE.

RAIL-FASTENING DEVICE.

1,318,640.

Specification of Letters Patent.

Patented Oct. 14, 1919.

Application filed October 15, 1917. Serial No. 196,748.

To all whom it may concern:

Be it known that I, JASMIN PIERRE BERGERON, a citizen of the United States, residing at Los Angeles, in the county of Los Angeles and State of California, have invented a new and useful Improvement in Rail-Fastening Devices, of which the following is a specification.

It is an improvement upon my invention disclosed in Letters Patent, 1,237,996, for rail-fastening device issued August 21, 1917.

This invention relates to an improvement in a rail fastening device, and especially to a device having a rail anchoring support, which is interposed between the rail and tie.

An object of this invention is to provide in conjunction with the rail-fastening means, other means incorporated therewith for a base of such form that the usual means heretofore employed of an additional tie-plate may be dispensed with.

Another object of this invention is to provide a wedge for securing a rail in place and improved means coöperating with said wedge to lock it in a more secure and efficient manner.

This invention comprises within the one construction a combination of three devices now used in attaining certain ends. These as now employed, are: the spikes, the tie-plate, and the rail anchor or anti-creeper.

To these ends, I employ a rail support or chair which is secured to the tie and has means for receiving the bottom flange of the rail, and a removable locking wedge which may be inserted in place, tightened or loosened, and removed without complicated means or the need of expert labor.

I accomplish these objects by means of the embodiment of my invention illustrated in the accompanying drawings, in which:

Figure 1, is an elevation of a tie having my improved rail fastening device applied thereto, the tie being shown broken at the center thereof. Fig. 2, is a fragmentary plan view. Fig. 3, is a side elevation. Fig. 4, is a perspective view of the rail support or chair. Fig. 5, is a perspective view of the locking wedge. Fig. 6, is a side view of the triangular locking pin. Fig. 7, is a section as seen on the line 7—7 of Fig. 6.

Referring more particularly to the drawings, 8 indicates an ordinary wooden tie, upon which a chair 9, preferably of metal is mounted. A locking wedge 10 is inserted

in the chair and overlying one edge of the rail 11.

The chair 9 comprises a flat base 12 having an under cut rib 13 formed at one side thereof, in which one edge of the flange of the rail is adapted to be disposed. At the opposite end of the chair a groove 14 is formed in the base for the reception of a locking wedge, which is preferably of metal. The side walls of the groove are undercut to securely hold the wedge in place. Depending from the bottom of the base and formed integral therewith are posts 15 and 16, which are provided with transverse openings 17 and 18. Openings are bored in the tie and in these the posts 15 and 16 are disposed. Suitably formed pieces of metal 19 and 20 are passed through small lateral bores in the tie and through the posts and clenched at the outer ends, thereby firmly securing the chair to the tie.

The rails 11 are now placed in position with one edge of the flange disposed under rib 13. Wedge 10 is now inserted in groove 14. Wedge 10 is provided with side walls 80 corresponding to the undercut walls of the groove, and it has a rib 21 overhanging the flange of the rail. Wedge 10 and groove 14 are tapered from front to rear. By forcing the wedge into the groove, pressure between 85 the rail and chair is increased, firmly securing the same. A lateral pressure is also exerted, which pushes the rail positively and firmly into the permanent holding portion of the support on the opposite side of the 90 rail. The space of the holding support on both flanges being many times that of a spike head, the resistance to shearing strain, which is especially large at curves, is greatly increased. The frictional binding of the 95 wedge also decreases the liability of loosening due to vibration. However, to avoid tampering and to insure against loosening, I have provided the wedge with positive means for retaining the same in place. 100

Formed in the base plate 12 is a series of openings 22 forming in effect a slot having teeth at the sides thereof. A slot 23 is formed at the wider end of the wedge 10, so that it may register with the slot 22. 105 A pin 24 of suitable shape so that it will fit the openings 22 is inserted in the slot 23 and in the opening at a point nearest to the end of the slot 23, and is then driven into the tie. Owing to the form of the pin and 110

the shape of the opening in the base, the pin has a tendency to be forcibly pressed against the end of the wedge. The bottom part of the pin being firmly held in the base 5 plate and in the tie, is therefore held in rigid relation thereto, but the upper part of the pin being free develops a certain elasticity or resiliency which is exerted against the wedge and acts to forcibly retain said 10 wedge in position against any vibrational movement tending to displace it.

By placing the chairs with the wedges on corresponding sides of the rail, the tie may be removed by sliding the latter from beneath the rail. The pins 24 are removed 15 and the wedges 10 are then forced from position. With the wedges removed, ties may be slid from under the rail, as will be noted by reference to Fig. 1.

20 It is obvious that I have eliminated the use of spikes by the pendent posts, which are a part of the base plate and adapted to be disposed in the fitted openings in the tie; that the rail is firmly held in place by the wedge 25 construction, and that this may be so firmly tightened that it will act positively as an anti-creeper; and that the extension of the base plate in actual practice becomes a tie plate.

30 What I claim is:

1. A rail fastening device comprising a base provided with means for securing it to a tie, said base being provided with means for engaging one edge of the flange of a rail, a locking wedge having means for engaging the opposite edge of the flange of the rail, said base being provided with a groove for slidably receiving said wedge and a series of longitudinally disposed vertical openings in the bottom of said groove for receiving a pin, said openings being so arranged that when a pin is disposed therein it will abut the wedge and lock the latter in place, thereby adjustably locking the wedge.

40 2. A rail fastening device comprising a base provided with means formed thereon for securing it to a tie, said base being pro-

vided with means for engaging one edge of the flange of a rail, a locking wedge having means for engaging the opposite edge of the flange of the rail, said base being provided with a longitudinally extending groove for slidably receiving said wedge, a series of longitudinally disposed openings in the bottom of said groove for receiving a pin, said openings being so arranged that when a pin is disposed therein it will abut the wedge and lock the latter in place, thereby locking the wedge.

3. A rail fastening device comprising a 60 base provided with means for detachably securing it to a tie, said base being provided with means for engaging one edge of the flange of a rail, a locking wedge having means for engaging the opposite edge of the flange of the rail, said base being provided with a channel for slidably receiving said wedge and a series of longitudinally disposed vertical openings in the bottom of said channel for receiving a pin, said openings being so arranged that when a pin is disposed therein it will abut the wedge and lock the latter in place, thereby adjustably locking the wedge.

4. A rail fastening device comprising a 75 base provided with means formed thereon for detachably securing it to a tie, said base being provided with means for engaging one edge of the flange of a rail, a locking wedge having means for engaging the 80 opposite edge of the flange of the rail, said base being provided with a longitudinally extending groove for slidably receiving said wedge, a series of longitudinally disposed openings in the bottom of said groove for receiving a pin, said openings being so arranged that when a pin is disposed therein it will abut the wedge and lock the latter in place, thereby locking the wedge.

In witness that I claim the foregoing, I 90 have hereunto subscribed my name, this 9th day of October, 1917.

JASMIN PIERRE BERGERON.
